Primary Examiner — Darlington Ly*Assistant Examiner* — Daniel J Domino(74) *Attorney, Agent, or Firm* — Morgan, Lewis & Bockius, LLP(57) **CLAIM**

The ornamental design for a display screen with graphical user interface, as shown and described.

DESCRIPTION

The FIGURE is a front view of a display screen with a graphical user interface.

The dot-dash broken line showing of a display screen and the regular broken lines showing elements of the graphical user interface illustrate portions of the article and do not form part of the claimed design.
